UNITED STATES PATENT OFFICE.

DENNIS O'BRIEN, OF OSWAYO, PENNSYLVANIA.

BARK-MILL.

SPECIFICATION forming part of Letters Patent No. 234,324, dated November 9, 1880.

Application filed August 13, 1880. (No model.)

To all whom it may concern:

Be it known that I, DENNIS O'BRIEN, of Os-
wayo, in the county of Potter and State of
Pennsylvania, have invented a new and useful
5 Improvement in Bark-Mills, of which the fol-
lowing is a specification.

The invention consists in combining a radially-slotted stationary plate provided with
10 grinding-teeth on one edge of each slot with
a wheel having teeth on the under side, as
hereinafter described.

In the accompanying drawings, Figure 1 is
15 a central vertical sectional view of a mill em-
bodying my improvements. Fig. 2 is a horizontal section. Fig. 3 is a detail view. Fig.
4 is a section taken in the line *y y* of Fig. 2.

Similar letters of reference indicate corre-
sponding parts.

A represents a cylindrical casing or cham-
20 ber, which incloses the working parts. B is a
vertical shaft, having its lower end stepped in
the bottom of the casing and its upper portion
journaled in a bar, C, extending diametrically
25 across the casing and having its ends secured
to the sides thereof. The edges of this bar C
(see Fig. 3) are provided with teeth *c*, for the
purpose hereinafter described.

D represents a wheel consisting of arms hav-
ing grinding-teeth on their lower surfaces, and
30 also on their ends. The portion of the casing
A immediately surrounding this wheel is pro-
vided with grinding-teeth for engagement with
the teeth on the ends of the arms of the wheel.
The upper portion of each arm is cut out, so
35 as to form a box-like cutting or breaking de-
vice having a bottom and two sides, one of
the sides being radial and the other parallel
with the outer end of the arm. The wheel
thus formed is attached to the shaft B, and
40 turns with it.

Immediately under the wheel D is a circular
plate, F, through the center of which the shaft
B passes. This plate is secured to the sides
45 of the casing, so as to remain stationary. It
is provided with radial slots *f*, of a width some-
what less than that of the arms of the wheel,
and of sufficient size to screen the bark it dis-
charges.

Each slot has grinding-teeth formed on one
50 edge. The plate is also provided with grind-
ing-teeth on both its upper and lower surfaces,
those on the upper surface being for engage-
ment with those on the under surfaces of the
arms of the wheel.

55 The bark to be broken and ground is thrown

into the casing or chamber A as the shaft B
revolves. The larger pieces of bark are caught
between the toothed bar C and the upper por-
tions of the arms of the wheel D and broken
into smaller pieces, which then pass between 60
the arms and are ground by the action of the
teeth of said arms and those on the casing
and on the slotted plate F, after which they
pass through the slots *f* to be passed out of
the machine.

G represents a slotted circular plate at-
tached to the shaft B by means of set-screws
g engaging with grooves *h*, so that said plate
may revolve with said shaft and yet be free
to rise and fall thereon, said shaft passing 70
through the center of said plate.

J represents a bar, one end of which is piv-
oted inside of the casing A, and the other end
passes out through a slot in said casing, and
is connected by a rod, *i*, with a lever, K, out-
side of the casing.

The upper surface of the plate G is provided
with teeth for engagement with those on the
under side of the stationary slotted plate F,
both of said series of teeth being finer than 80
those on the upper surface of the plate F.

When the bark has passed through the
slotted plate F, as before described, if it is
then found to be fine enough, it is allowed to
pass through the slots of the revolving plate 85
G and over its rim, the casing being widened
for the purpose, and drop to an inclined plane,
L, from whence it passes out of the casing
through an opening, *m*.

If it is desired to grind it still finer, the 90
lever K is raised, so as to elevate the bar J
and lift the revolving plate G, so that its teeth
will engage with those on the under surface
of the stationary plate F, after which it passes
through the slots of plate G to the inclined 95
plane, as before described.

Having thus fully described my invention, I
claim as new and desire to secure by Letters
Patent—

In bark-mills, the stationary plate provided
with radial slots *f*, having grinding-teeth on
one edge of each slot, in combination with the
wheel D, having grinding-teeth on its under
surface, as shown and described, for the pur-
pose specified.

DENNIS O'BRIEN.
